UNITED STATES PATENT OFFICE.

WILLIAM MORGAN PIPER, OF ALLEGHENY, PENNSYLVANIA.

DRAFT-RIGGING.

SPECIFICATION forming part of Letters Patent No. 609,701, dated August 23, 1898.

Application filed October 1, 1897. Serial No. 653,721. (No model.)

To all whom it may concern:

Be it known that I, WILLIAM MORGAN PIPER, of Allegheny, in the county of Allegheny and State of Pennsylvania, have invented a new and useful Improvement in Draft-Rigging, of which the following is a full, clear, and exact description, reference being had to the accompanying drawings, forming part of this specification, in which—

Figure 1 is a top plan view, partly broken away, of one form of my improved device. Fig. 2 is a longitudinal sectional view of the same; and Figs. 3 and 4 are views similar, respectively, to Figs. 1 and 2, showing another form of the device.

My invention relates to that class of devices for taking up strains of a compressive or pulling nature—such, for example, as set forth in my United States Letters Patent No. 566,935, dated September 1, 1896, wherein a block or blocks having oppositely-directed inclines are employed, these inclines contacting with a spring-actuated wedge or wedges—and is designed to provide an improved device of this character in which a series of the blocks and coacting wedges may be combined together compactly and in a small space and may coact in such a manner as to provide for cushioning shocks varying from a light to a very heavy blow.

To that end it consists in a series of separate cushioning devices, each device complete in itself, the devices being arranged side by side in tiers and acted upon by the longitudinally-movable bar.

It also consists in a series of the said blocks and wedges arranged side by side, either in a vertical or horizontal direction, these blocks being preferably arranged so as to act successively.

The invention further consists in the construction and arrangement of the parts, as hereinafter described, and set forth in the claims.

In the drawings, referring to Figs. 1 and 2, in which I show a quadruple arrangement of my device, 2 2 represent the draft-timbers of the car, 3 the end sill, and 4 the draw-bar, to which the ordinary coupler-head may be attached. The draw-bar rests upon the ordinary carry-iron 5, and to its rear end is se-

ured a yoke 6, which surrounds the draft device proper. This device in these figures consists of a quadruple arrangement of blocks and wedges arranged in two decks or tiers, 55 each tier having sliding end blocks 7 7, provided with inner oppositely-inclined faces, as shown, and an intermediate block 8, between which and the end blocks are located the pairs of wedges 9 9, which are normally forced apart 60 by the coiled springs 10. The inclined faces of the blocks and the faces of the wedges are preferably provided with corresponding ribs and grooves 11, by which the wedges are guided in their movements and held in proper 65 position. The rear end block of the lower pair is tied to the front end block of the upper pair by a connecting bar or bars 12, as shown in Fig. 2, so that any strain brought upon either tier will be transmitted to the 70 other tier.

13 are guide-plates secured to the inner sides of the draft-timbers and in contact with which the blocks move, these guide-plates being secured by through-bolts 14. To hold the 75 blocks and wedges in place during their movement, I provide top and bottom plates 15, which cover the edge portions of the blocks and are preferably secured in place by bolts passing through recesses formed by bending 80 or shaping the guide-plates as shown at 16. The front block of the upper tier is located slightly back of that of the lower tier, so that a compressive strain upon the draw-bar will cause the same to act first upon the front 85 block of the lower tier. The acting faces of this block are inclined at a comparatively sharp angle, that of the rear block of the lower tier being at a somewhat less angle, and the front and rear blocks of the upper tier 90 having successively smaller angles than that of the rear block of the lower tier, so that these four cushioning devices will act successively, they being preferably so arranged that the wedges of the lower tier will be forced 95 in their entire limit before the devices of the upper tier come into action. It is evident that this successive action of the devices may be obtained either by varying the strength of the springs employed between the wedges 100 or by varying the angles of the blocks and wedges, or by both, and I intend to cover the

arrangement of the cushioning devices and their successive action whether obtained in these or other ways.

To prevent injury to the draft-timbers and 5 hold the draft devices more firmly in position, I may employ straps or yokes 17, which surround the draft-timbers, the upper cross-bolts 18 of these yokes having pivoted dogs 19, which bear upon plates on the upper faces of 10 the draft-timbers. As these yokes engage the side plates or other suitable part of the draft device, any endwise strain upon such draft device will be communicated to the dogs, which will bind upon the draft-timber and 15 hold the parts firmly in place without the necessity for additional bolts, which would weaken the timbers.

In Figs. 3 and 4 I show a somewhat similar construction, wherein three tiers of the cushioning devices are employed, these tiers being used without connecting-bars, the end blocks of each tier being placed somewhat back of the end blocks of the next tier beneath, so that the draw-bar or its yoke, in 20 either direction of movement thereof, will act first upon the lower tier and then successively upon the upper tiers. Numerals with the exponent α in these figures designate the parts corresponding to the similar parts in Figs. 1 25 and 2.

In every form the springs and wedges are preferably so arranged that the wedges will reach the limit of their movement before the coils of the springs contact with each other, 30 thus preventing liability of breaking the springs.

The advantages of my invention will be apparent to those skilled in the art, since a draft device is thus provided which is compact and simple and which will cushion a strain of either a compressive or pulling nature, whether such strain be heavy or light.

The number of the wedges and coacting blocks, the angle of their coacting faces, and 45 the general form and arrangement of the parts may be varied without departing from my invention, since

I claim—

1. The combination of a series of separate 50 cushioning devices, each device being complete in itself and containing moving friction parts, the moving parts of one device being independent of those of the others, said devices being arranged side by side in tiers and 55 operating independently of each other, and a longitudinal bar extending transversely of

the series and arranged to act upon the devices.

2. The combination of a series of separate cushioning devices, each complete in itself, the series being arranged side by side in tiers, of a longitudinally-movable bar arranged to operate said devices successively.

3. The combination with a series of cushioning devices arranged side by side in different tiers, each device containing a block having oppositely-directed inclines, wedges contacting with the inclines, and a spring arranged to resist the movement of the wedges along the incline, of a longitudinally-movable bar arranged to actuate said devices.

4. The combination with a series of cushioning devices arranged side by side in tiers, each device containing a block having oppositely-directed inclines, and spring-pressed wedges contacting with the inclines, a connection between the block of one device and that of another, and a longitudinally-movable bar arranged to actuate the series.

5. The combination of a series of cushioning devices arranged side by side in tiers, each device containing a block provided with oppositely-directed inclines and spring-pressed wedges contacting with the inclines, a yoke surrounding the series, and a longitudinally-movable bar to which the yoke is secured.

6. The combination with a longitudinally-movable bar, of a yoke secured at the end thereof, transverse blocks arranged side by side in tiers within the yoke, the end block of one tier projecting beyond that of the other, and spring-pressed wedges coacting with oppositely-directed inclines upon the blocks.

7. A draft-rigging comprising a coupler having a draw-bar provided with an end yoke, a series of transverse blocks extending through the yoke and arranged side by side, said blocks having oppositely-directed inclines, spring-pressed wedges contacting with the inclines, and a connection between the end block of one tier and the opposite end block of the next tier.

8. A securing device for draft-rigging consisting of a yoke arranged to surround the draft-timber and having pivoted lugs arranged to bear thereon.

In testimony whereof I have hereunto set my hand.

WILLIAM MORGAN PIPER.
